DOOR KNOB OR SIMILAR ARTICLE

Vytant P. Aleks, Rockford, Ill., assignor to National Lock Co., Rockford, Ill., a corporation of Delaware

Application March 26, 1959, Serial No. 55,188

Term of patent 14 years

(Cl. D50—3)

Fig. 1 is a side elevational view of a door knob or similar article, embodying my new design;

Fig. 2 is a front elevational view thereof; and

Fig. 3 is a partial sectional view through the knob and the cap therefor, the view being taken on the line 3—3 of Fig. 2.

The characteristic feature of the design is the contour of the cap shown in Figs. 2 and 3.

I claim:

The ornamental design for a door knob or similar article, substantially as shown and described.
